(57) **CLAIM**

The ornamental design for tongs, as shown and described.

DESCRIPTION

FIG. 1 is a perspective view of the Tongs in a closed confirmation showing my new design.

FIG. 2 is another perspective view in a closed confirmation thereof.

FIG. 3 is a front view in a closed confirmation thereof.

FIG. 4 is back view in a closed confirmation thereof.

FIG. 5 is a side view in a closed confirmation thereof.

FIG. 6 is another side view in a closed confirmation thereof.

FIG. 7 is a top view in a closed confirmation thereof.

FIG. 8 is bottom view in a closed confirmation thereof.

FIG. 9 is a perspective view thereof in an open confirmation.

FIG. 10 is another perspective view thereof in an open confirmation.

FIG. 11 is a front view thereof in an open confirmation.

FIG. 12 is back view thereof in an open confirmation.

FIG. 13 is a side view thereof in an open confirmation.

FIG. 14 is another side view thereof in an open confirmation.

FIG. 15 is a top view thereof in an open confirmation; and,

FIG. 16 is bottom view thereof in an open confirmation.

The broken lines in the drawings illustrate portions of the tongs which form no part of the claimed design.
